HOLDER FOR HAND LINES

Tyko K. Finneman, 3226 SE. 25th Place, Portland, Oreg.

Filed Oct. 5, 1964, Ser. No. 82,036

Term of patent 14 years

(Cl. D41—1)

FIG. 1

FIG. 2

FIG. 3

I claim:

The ornamental design for a holder for hand lines, as shown.
